(57) **CLAIM**

The ornamental design for an eyewear with faceted lenses, substantially as shown and described.

DESCRIPTION

FIG. 1 is a perspective view of a first implementation of the invention.

FIG. 2 is a front view of the first implementation of the invention.

FIG. 3 is a back view of the first implementation of the invention.

FIG. 4 is a left view of the first implementation of the invention.

FIG. 5 is a right view of the first implementation of the invention.

FIG. 6 is a top view of the first implementation of the invention; and,

FIG. 7 is a bottom view of the first implementation of the invention.

The portions of the eyewear with faceted lenses shown in broken lines form no part of the claimed design.

1 Claim, 5 Drawing Sheets
